Patented Sept. 20, 1921.

FIG. 2.

By

Inventor
Attilio Conte
Lawrence Lawyer

Attorney

UNITED STATES PATENT OFFICE.

ATTILIO CONTE, OF BUENOS AIRES, ARGENTINA.

SAFETY DEVICE FOR LOCKS.

1,391,615.

Specification of Letters Patent. Patented Sept. 20, 1921.

Application filed July 16, 1920. Serial No. 396,740.

To all whom it may concern:

Be it known that I, ATTILIO CONTE, a subject of the King of Italy, residing at No. 1276 Avenida de Mayo, Buenos Aires, Argentina, have invented certain new and useful Improvements in Safety Devices for Locks, of which the following is a specification.

This invention relates to an improved safety device for locks which offers several advantages over locks of known construction and which allows of performing certain operations whereby an ordinary spring latch lock may be used as a key-controlled lock, by which arrangement its use and construction are considerably simplified and rendered less expensive, while obtaining at the same time a higher degree of safety.

This invention substantially consists in providing an ordinary spring latch lock with a pin adapted to lock the latch operating parts by entering into a hole in the shank of the latch bolt. The pin is provided with a projection, and the key-operated cylinder used for operating the lock and which may be of any suitable type, is formed with a helical cam adapted to raise said projection and in consequence release the latch of the lock. The pin passes through a boss provided with three grooves in which a stop on the pin is interchangeably engaged, so that three positions are obtained, corresponding with three operations of the lock, viz: one in which the lock operates with the key only; a second position in which the operation is effected by the handle only, and a third position in which the lock is blocked.

In order to facilitate the understanding of the invention, the same has been illustrated by way of example in the accompanying drawings, wherein:

Figure 1 illustrates a cross section of a lock constructed in accordance with the invention.

Fig. 2 shows a rear elevation of the same; Fig. 3 is a horizontal section of the lock, and

Fig. 4 is a detail view of the boss with its three grooves.

In all the several views, the same reference numerals have been used to indicate like or corresponding parts.

The known parts of the lock, such as the housing, the handle, the beveled latch bolt with its shank and the cylinder for the reception of the key, have been shown only by

way of example and it will be evident that the same may be of any other suitable construction as they do not form part of this invention. The cylinder 1 which is to be used when the lock is to be operated by a key, has been shown somewhat diagrammatically and is adapted to rotate when the proper key 2 is inserted therein. Said cylinder or the corresponding part of any other type of lock is provided with an axially operating helical cam 4 formed on the drum 3.

The cover 5 of the lock housing is provided with a hole for the passage therethrough of a pin 6, guided by the plate 7. A spring 8 normally pushes said pin inward and causes the same to pass through a hole 9 formed in the shank 10 of the beveled bolt 11. Near its end, the pin is provided with a stud or finger 12 adapted to take a position in the path of the helical cam 4, in which position said cam can raise the pin out of hole 9. Outside the casing, the pin is provided with a stop 13, adapted to enter into one of the three grooves 14, 15, 16 of a boss 17, formed integral with the cover of the lock.

18 indicates the spring for projecting the latch bolt, and 20 is the hub or rollback for bolt 11 and operable by handle 19, while 21 is a spring, arranged to return cylinder 1 to its normal position.

As has already been stated before, the present arrangement allows the lock to be operated under three different conditions which in connection with the drawings and the foregoing description will be readily understood.

Considering the first case, in which the lock is blocked against operation by the key or by the handle, it will be seen that these conditions are obtained by inserting the stop 13 into the groove 14 which is of sufficient depth to permit pin 6 to pass through the hole 9 in the shank 10 of the bolt, thereby preventing the handle from being operated. Since the groove 14 is so positioned that the finger 12 is out of the path of the cam, any turning of the key will not raise the pin; in consequence, the lock remains blocked or locked.

In the second case, the lock can be opened with the key, but not with the handle alone. For this purpose, the projection 13 is caused to engage with the groove 15. The pin still locks the shank but as it has turned to such an extent as to bring finger 12 into the path

of the cam, this latter, when turning, will raise the pin out of engagement with said shank whereupon the lock may be opened by operating the handle.

5 The third case, finally permits the lock to be operated by the handle in the same way as an ordinary spring-latch lock, this condition being attained by placing the stop into the third groove 16 which, being of less 10 depth than the former two, will hold the pin in its raised position with the finger 12 above the cam so that the shank is thus released.

Having now described my said invention, I declare that what I claim as new and desire to secure by Letters Patent, is:

1. In a key-operated, spring latch lock, a safety device consisting of a helical cam caused to rotate by the action of the key, a pin adapted to block the latch bolt of the 20 lock by penetrating into a hole formed in said bolt, said pin being provided with a finger adapted to engage with the cam, so that on the rotation of said cam the pin will be raised, a handle for operating the 25 latch bolt when released, a boss provided with three grooves, and a projection formed integral with said pin for interchangeable engagement in said grooves whereby said pin may be caused to assume an operative 30 position wherein its finger will be engageable by said cam, a second operative position in which its finger is out of the path of the cam, or a third position in which the pin will be held raised in inoperative position, 35 substantially as above described and for the purposes set forth.

2. In a key-operated, spring latch lock, the combination, with the latch bolt and its operating handle, of a movable key-operated 40 part, a pin engageable with said bolt to lock the same against operation, said pin having a projection thereon, a member on said key-

operated part for coaction with said projection to disengage the pin from the bolt, and means to selectively hold said pin in any 45 one of three predetermined positions, in one of which the pin and bolt are engaged but the projection on said pin is inactive with relation to the member on the key-controlled part, in the second of which the pin and bolt are engaged and the projection is active with relation to said member, and in the third of which the pin and bolt are disengaged.

3. A key-operated, spring latch lock according to claim 2, in which the selective 55 holding means comprise a boss having three angularly-arranged grooves to interchangeably receive a stop on the pin, the latter being rotatably mounted to shift the stop to position to engage a selected groove.

4. In a key-operated, spring latch lock, the combination, with the latch bolt and its operating handle, of a rotatable key-operated 60 part, a part movable into and out of engagement with the bolt to lock and unlock the 65 same, coacting means on the locking part and the key-operated part to disengage the former from the bolt, and means for selectively holding said locking part in any one of three predetermined positions, in one of 70 which the locking part and the bolt are engaged but the coacting means are inactive, in the second of which said locking part and said bolt are still engaged but the coacting means are active, and in the third of 75 which the locking part and the bolt are disengaged.

In testimony whereof, I hereunto affix my signature in presence of two witnesses.

ATTILIO CONTE.
